ACTUATING MECHANISM

Clyde G. Isham, South Bend, Ind., assignor to The Bendix Corporation, South Bend, Ind., a corporation of Delaware

Filed June 29, 1962, Ser. No. 206,324
4 Claims. (Cl. 74—110)

This invention relates to actuators and, in particular, to a condition responsive mechanical actuator responsive to one or more conditions and having an output position indicative of one or more of said conditions.

In automated mechanisms such as punch presses, assembly mechanisms and the like, where automatic operation has proved highly advantageous, it is customary to provide safety devices which sense and respond to certain conditions such as work stoppages, misaligned mating component parts, and other similar conditions which, if not protected against, could disrupt operation and result in damage to the automated system.

It is the usual practice to provide switches wired in the electrical system which controls the operation of the automated mechanism, which switches are arranged to be contacted and actuated to an off position to thereby render the automated mechanism inoperative by probes, pilots, etc., which are located to sense a particular condition which indicates an operating malfunction. In many instances, a plurality of conditions must be monitored by such probes, pilots, etc., each of the latter being arranged to actuate a single associated switch. The addition of a plurality of such switches to the control system of the automated mechanism represents additional cost as well as adding to system complexity and, in structures where space is not readily available, creates design problems. It is therefore an object of the present invention to provide a mechanical actuator responsive to any one or more of a plurality of mechanical input motions and having a single output motion in response to said one or more input motions.

It is another object of the present invention to provide a simple and compact mechanical actuating mechanism.

Other objects and advantages of the present invention will become apparent from the following detailed description of one preferred embodiment taken in conjunction with the accompanying drawings wherein:

FIGURE 1 is a cross section view of a punch press embodying the present invention;

FIGURE 2 is a schematic plan view of the lower portion of the press of FIGURE 1 showing the various steps of sequential operation including the final probe operation which involves applicant's invention; and

FIGURE 3 is a plan view partially cut away to expose applicant's actuating mechanism taken on line 3—3 of FIGURE 1.

FIGURE 4 is a fragmentary sectional view showing reciprocal rod or shaft members in switch actuating position.

Referring to FIGURE 1, numeral 10 represents an automatic punch press having a fixed bed portion 12 and a vertically movable ram portion 14 to which a die table 16 and punch holder 18, respectively, are fixedly secured by conventional fastening means, not shown. An index table 20 is rotated about an axis A, FIGURE 2, by conventional control apparatus, not shown, to thereby effect sequential punch operations as shown in FIGURE 2 which include the steps of automatic loading, extrusion, trim, idle, coin and knock out, and probe in the order named. Since automated punch presses of this general type are used extensively in industry and the structure and operation of the same well known to those skilled in the art, it is not believed necessary to show or describe the structure or operation of the automatic press 10 be-

2

yond that required to show the operating relationship of applicant's invention with the press 10. It will be understood that the movable ram portion 14 is provided with the necessary punches, etc., which cooperate with the mating die carried by the index table 20 to effect the operation indicated at each of the six positions through which the die is indexed. The present invention is concerned with the probe operation immediately prior to the automatic loading operation and, in the following description, it will be assumed that the loading operation consists of supplying a circular metal slug to each of four die cavities 24 as each die 26 is moved into position in response to indexing of table 20 for loading by the automatic loading apparatus. As shown in FIGURE 1, the metal slugs are reduced to a piston-like member 28 which is normally ejected from the die cavities 24 at the coin and knock-out operation immediately prior to the probe operation.

It is essential that the die cavities 24 be clear of any obstructions such as members 28 when the metal slugs are introduced thereto by the loading operation. If the cavities 24 are not clear, the press 10 must be disabled temporarily to permit removal of the obstructions by hand before the sequence of punch operations is resumed. To this end, for each die cavity 24, applicant provides an associated probe 30, 32, 34 or 36 slidably carried in spaced apart vertical bores 38, 40, 42 and 44, respectively, in punch holder 18. The spacing of the four die cavities 24 shown in FIGURE 2 and the spacing of probes 30, 32, 34 and 36 associated therewith shown in FIGURE 3 does not correspond by virtue of FIGURE 2 being of reduced scale. However, it will be understood that the probes 30, 32, 34 and 36 enter their associated die cavities 24 on the downward stroke of ram portion 14 to test for existence of the abovementioned obstructions. A bore 46 having an axis perpendicular to and intersecting the axes of bores 38 and 40 extends through punch holder 18. A second bore 48 having an axis perpendicular to and intersecting the axes of bores 42 and 44 also extends through punch holder 18. A bore 50 having an enlarged diameter end portion 52 extends through punch holder 18 and is arranged with its axis perpendicular to and intersecting the axes of bores 46 and 48.

Shafts 54 and 56 slidably carried in bore 50 are provided with beveled end portions 58 and 60, respectively. Shafts 62 and 64 slidably carried in bore 46 are each provided with a beveled end portion 66 similar to portion 58 against which the end portions 66 bear in line contact. Shafts 68 and 70 slidably carried in bore 48 are each provided with a beveled end portion 72 similar to portion 60 against which the end portions 72 bear in line contact. The shafts 62, 64, 68 and 70 are each provided with a rounded end portion 74 which extends into an associated V-shaped annular recess 76 formed in probes 30, 32, 34 and 36.

The shaft 54 is provided with a reduced diameter end portion 77 which terminates in a beveled wall portion 78 similar to the beveled end portion 60.

A spring 80 interposed between an annular flange 82 formed on shaft 56 and a plug 84 threadedly secured in enlarged diameter end portion 52 serve to bias the shaft 56 into engagement with shaft 54 and effect engagement of beveled end portion 58 and 60 with beveled end portions 66 and 72, respectively. The shafts 62, 64, 68 and 70, in turn, are biased toward their respective probes 30, 32, 34 and 36 causing the rounded end portions 74 to engage annular recesses 76 thereby securing probes 30, 32, 34 and 36 in position axially. The shaft 56 which extends through and is slidably engaged with plug 84 extends into engagement with a spring loaded switch 86. The switch 86 is provided with terminals 88 and 90 which are wired into the electrical network, not shown, which controls the

operation of the punch press 10. As shown in FIGURE 3, the switch 86 is in an "on" position thereby permitting the punch press 10 to operate.

Now assuming the ram portion 14 to have commenced its downward travel and further assuming that one of the die cavities 24 is obstructed by a member 28 as indicated in FIGURE 1, the probes 30, 32, 34 and 36 will enter their respective die cavities 24. The probe associated with the obstructed die cavity 24, for instance probe 36, will contact the member 28 which forces the probe 36 upwardly in bore 44 thereby forcing the end portion 74 out of recess 76 and displacing shaft 70 toward reduced diameter portion 77. The beveled end portion 66 of shaft 70 bears against beveled end portion 60 causing shaft 56 to move downwardly away from shaft 54 against the resistance of spring 80 to the position shown in FIGURE 4 and actuates switch 86 to its open position which, in turn, opens the electrical network controlling press 10 to thereby stop the operation of the press 10. The obstruction in die cavity 24 then may be removed by any suitable means such as a hand operated tool. The probe 36 is a relatively loose fit in bore 44 and may be pulled downwardly by hand to the position where end portion 74 can enter annular recess 76 allowing shaft 70 to move away from reduced diameter portion 77 in response to the force of spring 80 tending to urge shaft 56 and thus beveled end portion 60 upwardly relative to beveled end portion 66. The shaft 56 engages shaft 54 thereby urging shaft 54 upward which, in turn, causes beveled end portion 58 to ride against beveled end portions 66 of shafts 62 and 64 thus maintaining a preload on the latter shafts which must be overcome before rounded end portions 74 can slip out of the annular recesses 76 associated with probes 30 and 32. In the same manner the preload applied by shaft 54 to shafts 68 and 70 through beveled end portions 60 and 66 must be overcome before the rounded end portions 74 can slip out of the annular recesses 76 associated with probes 34 and 36. The preload applied in the abovementioned manner to shafts 62, 64, 68 and 70 is sufficient to overcome any tendency of the probes 30, 32, 34 and 36 to move upwardly in their respective bores as the probes enter their respective die cavities 24 unless an obstruction is present in one or more of the cavities 24 in which case the preload would be overcome in the abovementioned manner.

An obstruction in the die cavity 24 associated with probe 42 would effect movement of shaft 56 via shaft 68 in the manner heretofore mentioned with regard to shaft 70 to actuate switch 86 to its open position. Upon removal of the obstruction in cavity 24, the probe 42 would be reset in the aforementioned manner thereby returning the various shafts 54, 56, 62, 64, 68 and 70 to the positions shown in FIGURE 3 whereupon the punch press 10 is returned to normal operation.

In the event that one or both of the probes 30 and 32 react to an obstruction in this respective die cavities 24, the shaft 54 would be urged downwardly, as viewed in FIGURE 3, causing abutting shaft 56 to move accordingly against the force of spring 80 to actuate micro-switch 86 to its open position thereby disabling the punch press 10. In such a case, it will be understood that the axial length of reduced diameter portion 77 is sufficient to permit shaft 54 to move the required distance without interference between beveled wall portion 78 and the beveled end portions 66 of shafts 68 and 70.

While only four probes 30, 32, 34 and 36 are shown and described, it will be understood that a greater or smaller number of such probes may be used depending upon the number of conditions to be sensed. For instance, additional shafts similar to shaft 54 can be arranged end-to-end in bore 50 to duplicate the configuration illustrated in FIGURE 4 and thereby provide for an additional one or more probes.

Various other adaptations and modifications of the

present invention may be made by those persons skilled in the appropriate art without departing from the spirit of the present invention.

I claim:

1. A mechanical actuating mechanism responsive to one or more of a plurality of mechanical input motions and having a mechanical output motion comprising:
a casing having a first bore formed therein,
a first shaft slidably carried in said first bore and provided with a first beveled end portion,
a second bore in said casing and extending transversely to and intersecting said first bore,
second and third shafts slidably carried in said second bore on opposite sides of said first bore and provided with second and third beveled end portions, respectively, which mate with said first beveled end portion,
third and fourth bores in said casing extending substantially perpendicular to said second bore,
first and second condition responsive means slidably carried in said third and fourth bores, respectively, and movable in response to associated conditions sensed thereby,
a recess formed in each of said first and second condition responsive means for receiving a curved end portion of said second and third shafts, respectively, resilient means operatively connected to said first shaft for imposing a preload thereagainst to thereby maintain said first beveled end portion in contact with said second and third beveled end portions and establish a preload against said second and third shafts which forces said curved end portions thereof into said recesses provided therefor,
said first and second condition responsive means being operative independently of one another in response to the conditions sensed thereby and movable in said third and fourth bores to force said curved end portions out of said recesses causing said second and third beveled end portions to ride against said first beveled end portion thereby actuating said first shaft against the resistance of said resilient means to a predetermined output position indicating the occurrence of said conditions.

2. A mechanical actuating mechanism responsive to one or more of a plurality of mechanical input motions and having a mechanical output motion comprising:
a casing having a first bore formed therein,
a first shaft slidably carried in said first bore and provided with a first beveled end portion,
a second shaft having a second beveled end portion and a reduced diameter end portion abutting said first beveled end portion,
said second shaft being slidably carried in said first bore,
second and third bores in said casing extending transversely to and intersecting said first bore,
third and fourth shafts slidably carried in said second and third bores, respectively, and provided with third and fourth beveled end portions, respectively,
said third beveled end portion engaging said first beveled end portion and said fourth beveled end portion engaging said second beveled end portion, third and fourth bores in said casing extending substantially perpendicular to and intersecting said second and third bores, respectively,
first and second condition responsive probe members slidably mounted in said third and fourth bores, respectively, and provided with recesses for receiving a curved end portion of said third and fourth shafts, respectively,
resilient means operatively connected to said first shaft for biasing the same into engagement with said second shaft and urging said first and second beveled end portions, respectively, against said third and fourth beveled end portions,

said first and second condition responsive probes being held in position by said curved end portions engaging said recesses in response to the force derived from said resilient means acting through said beveled end portions and associated first and second shafts, 5 said first and second condition responsive probes being operative independently of one another in response to the condition sensed by each and actuated in their respective third and fourth bores to thereby force the curved end portion of their respective third and fourth shafts out of the associated recess causing said third and fourth beveled end portions to ride against the associated first and second beveled end portions, said first shaft being actuated against the resistance of said resilient means to a predetermined output position indicating the response of said first condition responsive probe,

said second shaft and said abutting first shaft being actuated against the resistance of said resilient means to a predetermined output position indicating the response of said second condition responsive probe.

3. A mechanical actuating mechanism as claimed in claim 2 wherein said reduced diameter end portion provides for relative movement between said second shaft and said third beveled end portion.

4. A mechanical actuating mechanism responsive to one or more of a plurality of mechanical input motions and having a mechanical output motion comprising:

a casing having a first bore formed therein,
first means slidably carried in said first bore and provided with a first beveled end portion, 30
second means slidably carried in said first bore and provided with a second beveled portion and a reduced diameter end portion abutting said first beveled end portion, 35
a second bore formed in said casing,
third means slidably carried in said second bore and

provided with a third beveled portion slidably engaged with said first beveled portion,
a third bore formed in said casing,
fourth means slidably carried in said third bore and provided with a fourth beveled portion slidably engaged with said second beveled portion,
resilient means operatively connected to said first means for imposing a load thereagainst in a direction to maintain said first beveled portion and said reduced diameter portion in abutting relationship thereby urging said second beveled portion into engagement with said fourth beveled portion and said first beveled portion into engagement with said second beveled portion,
input motion producing means operatively connected to each of said second and fourth means for actuating either of the same independently of the other, said third means being operative through its associated third beveled portion and the first beveled portion of said first means to urge said first means out of contact with said second means thereby producing a predetermined output motion of said first means,
said fourth means being operative through its associated fourth beveled portion and the second beveled portion of said second means to urge said second means and said first means against the resistance of said resilient means thereby producing a predetermined output motion of said first means.
